UNITED STATES PATENT OFFICE.

THOMAS H. WELCH, OF HAWTHORNE, NEW YORK, ASSIGNOR OF ONE-THIRD TO
HORACE K. CURTIS AND ONE-THIRD TO JOHN I. D. BRISTOL, BOTH OF CHAP-
PAQUA, NEW YORK.

RADIATOR PROTECTOR.

Application filed November 16, 1921. Serial No. 515,651.

To all whom it may concern:

Be it known that I, THOMAS H. WELCH, a citizen of the United States, residing at Hawthorne, in the county of Westchester 5 and State of New York, have invented certain new and useful Improvements in Radiator Protectors, of which the following is a specification.

This invention relates to automobile accessories and has particular reference to means co-operating with the radiator to prevent freezing of the water therein in cold weather and so to keep the engine as nearly as possible at the temperature most adaptable for efficient operation of the machine.

Among the objects of the invention is to provide a shield or guard for co-operation with a portion of the radiator for the purpose of reducing the radiating surface when the water is in danger of being reduced to too low a temperature.

Another object of the invention is to provide a shield or guard member with means for attaching it quickly, conveniently, and neatly in place, and at a cost so low as to make the device easily within the reach of the owner or operator of any popular type of automobile, and a device at the same time which I have found to be exceedingly well adapted for its purpose.

A still further object of the invention is to provide attachment means for a radiator protector of such a nature that the device may be attached to or disconnected from the radiator almost instantly, but when in use will be so held as to be secured reliably and not liable to become loose accidentally.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a front elevation.

Fig. 2 is a vertical transverse section on the line 2—2 of Fig. 1.

Fig. 3 is a detail perspective view of one of the springs.

Fig. 4 is a similar view of one of the locking keys.

Referring now more specifically to the drawings I indicate at 10 a conventional radiator including vertical tubes 11 to which are attached fins 12.

13 indicates a substantially flat sheet of suitable material preferably of a moisture and heat proof composition, such as rubberoid or its equivalent, the same being of a length corresponding to the full width of the radiator and of a height sufficient to protect as much of the radiator front as may be desired according to the weather, to prevent the cold air from going into direct contact with the portion of the radiator that requires to be protected. At each end the sheet or plate 13 is provided at the upper and lower corners with horizontally arranged grooves 14, and vertically between the grooved portions of said corners is formed a hole or slot 15.

A bowed spring member 16 is shown provided for each end of the shield, and each spring is provided with a foot portion 17 having a bead or projection adapted for co-operation with any selected grooves or slots 14, the grooves being so arranged as to prevent lateral or rotary displacement of the springs in practice. The central portion of each spring is bent or bowed forward so as to lie about an inch, more or less, from the front surface of the guard 13, and said central portion of each spring is provided with a slot 18 in registry with the slot 15 of the guard. As a locking means for each spring I

show a key 19 having at its rear or inner end a sharply bent hook 20 and at its front end is a head or ring 21 the diameter of which is slightly greater than the length of the slot 18 so that a portion of the ring lies within the slot 18 and thereby the key is held from rotation. Moreover the position of the head indicates to the operator the position of the point of the hook to facilitate the attachment or detachment of the device.

To connect the guard to the radiator it is simply put in place as indicated, and the springs are then put in place in succession, a key being projected rearward through the slot 18 of each spring and thence through the slot 15 of the guard, the hooks of the keys being passed rearward through the

radiator and engaged over or around the rear edge of any convenient fin or fins. The springs are shaped and the length of the hooks is so designed that in order to hook them over the fin or fins the springs must be put under a sufficient degree of compression so as to serve to hold the keys in hooked position and thereby the springs will be held in position with the projections 17 thereof in the grooves 14, and so in turn the guard will be held locked in the desired position on the front of the radiator. The point 22 of each hook is relatively broad and lies away from the body of the key while the remaining portion of the hook will lie parallel and close to said body. This form facilitates the engagement of the hook around the fin and reduces the possibility of either rattle or accidental disconnection of the parts. Furthermore the point of the hook is preferably flat or chisel-shaped, giving a more secure engagement with the fin and with minimum likelihood of bending the fin. As a further means to prevent displacement of the guard, either upward or laterally or downward, the body thereof to form the corrugations 14 is projected rearward so as to lie between the horizontal fins and also, longitudinally of the guard, it will lie between the vertical 30 water tubes. These corrugations serve primarily to prevent creeping of the guard along the radiator front in any direction, the springs and keys holding the same in said position.

35 I claim:

1. In a radiator protector, the combination with a radiator having a front provided with horizontal and vertical parts forming spaces, of a guard member lying flat against the radiator front and having projections extending from its rear surface into said horizontal and vertical spaces, and means to hold said guard in such position.

2. A device as set forth in claim 1 in which the guard member is formed of moisture and heat proof material and is provided with a plurality of corrugations formed in its front surface and so shaped as to constitute rearward projections, and wherein the holding means includes a plurality of members fitted against the front of the guard and into certain of said corrugations.

3. The herein described radiator protector comprising a guard member for co-operation with the front of the radiator, and means to detachably lock the guard member in place, said means including a plurality of springs of flat material but bowed forward from the front of the guard member, parts of the springs engaging the guard member, and key means cooperating with

the radiator and engaging the portions of the springs bowed forward from the guard member.

4. In a radiator protector, the combination of a guard member and means to detachably lock the same against the front surface of the radiator, said locking means including a pair of springs having the end portions thereof bearing against the guard member while the middle portions of the springs are extended forward from the guard member, and key means cooperating detachably with the radiator and engaging the forward portions of the springs and serving to hold the same backward with the springs under compression and whereby the key means are held in place.

5. A device as set forth in claim 4 in which each spring at its forward portion is provided with a slot and the co-operating key is projected into said slot and thereby held from rotation with respect to the spring.

6. A device as set forth in claim 4 in which the spring is provided at its forward portion with an opening through which the associated key member is projected rearward having at its rear end a hook having a flat point for engagement over the rear edge of a radiator fin.

7. The combination with a radiator having horizontal and vertical front spaces and a plurality of flat metal fins adjacent thereto, of a protector comprising a guard member lying against the front of the radiator and having a plurality of corrugations struck backward therewith forming grooves in front and projections at the rear for co-operation with the radiator spaces, a plurality of springs placed against the front of the guard member, each spring having end portions fitted into certain of said corrugations and having a forwardly projecting portion with a slot formed therethrough,

and a key for each spring including at one end a hook for passage through said spring slot, thence through the guard member, and thence between adjacent fins and engageable over one of the fins, and having at its other end a flat head having interlocking co-operation with the slot of the spring and in the same vertical plane as the hook.

8. The herein described guard holding key for radiator protectors, the same having on one end a loop-shaped head and at the other end a sharply turned hook having a broad flat point lying in a plane perpendicular to the plane of the head.

In testimony whereof I affix my signature.

THOMAS H. WELCH.
